ELECTROLYTIC CELL FOR RECOVERING
MANGANESE

James H. Jacobs, Boulder City, Nev., and Warren H. Yarroll, Provo, Utah, assignors, by mesne assignments, to Crimora Research and Development Corporation, Crimora, Va., a corporation of Virginia.

Application November 16, 1944, Serial No. 563,692

3 Claims. (Cl. 204—263)

1

This invention relates to electrolytic cells of the compartment type employed in winning or recovering manganese or similar metals to remove anodic sludge from the cell and to improve the efficiency. More particularly, the invention applies to electrolytic cells of the type wherein the anodes are suspended in a compartment and separated from the cathodes by porous diaphragms. Among other objects, the invention aims to provide a cell structure in which a single feed line for the electrolyte may be employed in place of separate feed lines for each cathode. Another aim is to provide a cell structure in which all of the cathodes are suspended in a common catholyte of substantially uniform composition which leads to uniformity of deposition on the cathodes. Still another aim is to provide a cell structure so designed that the volume of catholyte, relative to that of anolyte, may be greatly increased without the difficulties caused by expanding bags of diaphragms filled with sludge, which have been encountered in previous attempts to maintain such a relationship without increasing the electrode spacing. This arrangement makes the control of pH and solution concentrations easier and less critical.

A further and very important aim is to provide an electrolytic cell structure capable of carrying a large volume of catholyte, per cathode, without increasing the spacing of the electrodes, so that the manganese introduced in the feed solution will have a long period of residence, as catholyte, in the cell. As a result, the cell can be operated at a much higher current density or capacity than has heretofore been possible. The main idea is to increase the amount of manganese which may be removed from a given amount of the solution passing through the cell, thereby effecting a corresponding decrease in the necessary size and cost of the leaching and purification plant required.

Other aims and advantages of the invention will appear in the accompanying description of an illustrative embodiment of apparatus for practicing the method, disclosed in the accompanying drawing, wherein:

Fig. 1 is a side elevation, of a cell embodying the invention, parts being broken away and other parts, including an anode and its diaphragm-covered frame, being shown in section;

2

Fig. 2 is a sectional view taken on the line 2—2 of Fig. 3, showing the diaphragm-covered frame in top plan;

Fig. 3 is an enlarged face view of the anode diaphragm covered frame with the anode inserted therein; and

Fig. 4 is a partial transverse sectional view through the center of the cell showing an anode diaphragm-covered frame and an anode suspended therein.

Heretofore, in compartment type cells employed for electro-winning manganese and similar metals, the anodic sludge has been allowed to collect at the bottom of the anode compartment when the cathodes were enclosed within diaphragm-covered frames or in the bottoms of anode bags when the anodes were completely enclosed in porous diaphragms. In both cases, the sludge accumulation has caused considerable difficulty. To ameliorate this difficulty, increased electrode spacing and increased volume of the anode compartment have heretofore been necessary. The disadvantages of these measures are obvious. When the anodes are completely enclosed within diaphragm bags or covers, the bags will eventually fill up with accumulated sludge and burst. This invention provides a cell structure having means whereby the anodic sludge is continuously removed from the space between the anodes and cathodes, thereby making it possible to maintain a large volume of catholyte, relative to the anolyte, without increasing the electrode spacing and the size of the cell. Incidentally, this arrangement is such that the cell can be operated at a much higher efficiency and the canvas covers or diaphragms enclosing the anodes will last much longer than the anode bags heretofore employed.

Referring to the illustrated embodiment of the cell structure, there is shown a box-like compartment 1, which may be made of wood or other suitable material which will not be affected by the electrolyte solution. It is shown as carrying suspended anodes 2 mounted on transverse bars 3, contacting bus bars 4 at their opposite ends, and these anodes are guided into frames 5 also suspended in the compartment and having canvas diaphragms 6 on opposite sides. Cathode plates 7 are suspended in the compartment from transverse bars 8 contacting bus bars 9 at their op-

posite ends. These plates may be carried in suitable frames (not shown) which may be made of phenolic resin or other suitable material. The frames are guided in place by suitable notched spacers 10.

In accordance with this invention, the lower portion of the box or cell compartment is shown as being provided with a false bottom 11 preferably made of wood and spaced above the bottom of the box to provide a lower sludge chamber. Herein, the false bottom is shown as having a rectangular opening, the width of which is determined by the width of the anode frames, and transverse spacer blocks or wooden strips 12 are arranged below the alternate cathode frames, providing spaces to receive the open bottoms of the anode frames to separate the sludge chamber from the upper main cell compartment. The lower, open ends of the anode frames, covered by the canvas diaphragms, are arranged to discharge directly into the sludge chamber at the bottom of the box or cell.

Purified feed solution is delivered to the catholyte through a single conduit 13, preferably arranged at one end of the compartment, and the anolyte is discharged from the sludge chamber through a discharge pipe 14. In this instance, the discharge pipe is shown as rising to a point above the false bottom and extends outwardly through the end wall of the cell at the desired level of the solution in the cell, so that the anolyte will be discharged by gravity flow.

An ordinary wood launder (not shown) is employed to convey the spent electrolyte to a storage tank, from which it is adapted to be pumped to the leaching plant for leaching more reduced ore. The accumulated sludge is discharged periodically through a sludge conduit 15, in the bottom of the sludge chamber. The bottom is provided with a sump portion to facilitate draining all the sludge by gravity flow.

The electrolyte in the cell is preferably cooled in the usual manner, by circulating cold water through suitable coils (not shown) which are made of lead pipe. The water may be artificially cooled in summer by employing mechanical refrigeration.

In the operation of the electrolytic cell, the anodes have to be removed periodically, say, at intervals of every six or eight weeks so that the plates may be cleaned and the clogged anode diaphragms replaced. Calcium sulphate crystals form on the inside of the anode diaphragms and reduce their porosity to such an extent that the solution will not flow through them. Therefore, it is necessary to replace them when the plates and frames are removed.

The cathodes are preferably, though not necessarily, made of special, stainless steel and the bars are preferably covered with lead; while the anodes are preferably composed of about 99% lead and 1% silver, drilled with holes so as to eliminate about 40% of the area. Such anodes produce a minimum amount of sludge of high density.

The cell is operated continuously and the cathodes may be removed at about twenty-four hour intervals and dipped into the usual solution of potassium or sodium dichromate, to prevent oxidation of the manganese and they are then washed in a spray tank and air-dried. The deposited manganese is stripped from the cathode plates in the usual manner, with the recovery of practically all of the metal.

The following is an example of the operation of a cell employing the invention:

5	Anode	99% Pb, 1% Ag 15" x 32" x 3/4"
		40% void
		28 anodes per cell
	Cathode	{ Type 316 stainless steel containing 18% Cr, 8% Ni and 2% Mo 18" x 32" by 1/8"
		27 cathodes per cell
10	Current density, anode	81 to 90 amp. per sq. ft.
	Cell voltage	5.0-5.3 volts
	Feed solution	{ Mn: 34 to 38 grams per liter (NH ₄) ₂ SO ₄ : 135 to 140 grams per liter SO ₄ : 0.15 gram per liter
	Catholyte	{ Mn: 8 to 10 grams per liter (NH ₄) ₂ SO ₄ : 155 grams per liter (calculated from ammonia content) SO ₄ : 0.10 gram per liter
15	Anolyte	{ Mn: 8 to 10 grams per liter (NH ₄) ₂ SO ₄ : 135 to 140 grams per liter H ₂ SO ₄ : 43 to 50 grams per liter
	Diaphragm	18-oz. canvas
	Duration of electrolysis	24 hrs.
	Pounds Mn per cathode	10 to 12
	Current efficiency	60 to 65 per cent

20 Obviously, the invention is not restricted to the particular embodiment thereof herein described but the cell structure is capable of a wide variety of changes within the scope of the 25 appended claims.

Having thus described the invention, what is claimed is:

1. An electrolytic cell for recovering manganese, comprising, in combination, a box; a plurality of 30 anode and cathode plates suspended therein with their opposite side edges spaced from the opposite side walls of the box, frames for the anodes carrying solution permeable diaphragms spaced from opposite sides of and completely surrounding each anode, except at its upper and lower ends and providing individual anolyte compartments having open lower ends, all of the cathode plates being located in a common catholyte compartment; a false bottom in the box 35 having openings into which the lower ends of said anode frames project and providing a sludge chamber into which the anodic sludge discharges freely by gravity flow; means to supply feed solution to the catholyte compartment; and a discharge conduit connected to the sludge chamber through which spent anolyte is drained as the feed solution is supplied.

2. An electrolytic cell of the character described 50 comprising in combination, a box having a false bottom therein dividing it into an electrolyzing chamber and a sludge chamber; cathodes and anodes suspended in the box and spaced from the sides of the box; solution-permeable diaphragms spaced from the opposite sides of each anode extending downwardly to said false bottom and also spaced from the sides of the box, thereby providing individual anode compartments, segregated from a common catholyte compartment; 55 said false bottom being impermeable to the catholyte solution between the anode compartments and having openings communicating directly with each anode compartment to permit anodic sludge to gravitate therethrough into the sludge chamber; means to supply electrolyte to the catholyte compartment; and an outlet conduit 60 connected to the sludge chamber to discharge spent anolyte therefrom as the electrolyte is replenished.

3. An electrolytic cell, as set forth in Claim 1, 65 wherein the discharge conduit extends upwardly from the sludge chamber to the level of the anolyte in the anolyte compartments; and a 70 drain pipe connected to the bottom of the sludge

5

chamber for periodically discharging the accumulated sludge therefrom.
